[57] CLAIM

The ornamental design for an exercise towel, as shown and described.

DESCRIPTION

FIG. 1 is a perspective view of an exercise towel showing my new design;

FIG. 2 is a top plan view thereof;

FIG. 3 is a bottom plan view thereof;

FIG. 4 is a left elevational view thereof and the right side elevational view is a mirror image thereof;

FIG. 5 is a front elevational view thereof;

FIG. 6 is a rear elevational view thereof;

FIG. 7 is a perspective view of another embodiment of an exercise towel showing my new design;

FIG. 8 is a top plan view thereof;

FIG. 9 is a bottom plan view thereof;

FIG. 10 is a left elevational view thereof and the right side elevational view is a mirror image thereof;

FIG. 11 is a front elevational view thereof; and,

FIG. 12 is a rear elevational view thereof.
